Primary Examiner — Cynthia R Underwood(74) *Attorney, Agent, or Firm* — McClure, Qualey & Rodack, LLP(57) **CLAIM**

The ornamental design for a shell of an electronic device as shown and described.

DESCRIPTION

FIG. 1 is a front, bottom and right side perspective view of a shell of an electronic device showing my new design;

FIG. 2 is a front view of FIG. 1;

FIG. 3 is a rear view of FIG. 1;

FIG. 4 is a left side view of FIG. 1;

FIG. 5 is a right side view of FIG. 1;

FIG. 6 is a top view of FIG. 1;

FIG. 7 is a bottom view of FIG. 1;

FIG. 8 is a rear, bottom and left side perspective view of FIG. 1; and,

FIG. 9 is an enlarged view of the portion 9 encircled in FIG. 1.

The broken lines in the drawings are for illustrative purposes and represent unclaimed and enlarged portions of the shell of the electronic device and therefore form no part of the claimed design. The dot-dash broken lines define the bounds of the claimed design and form no part thereof.
